FIG. 1 is a perspective view of a golf tee showing my new design;

FIG. 2 is a side elevational view thereof;

FIG. 3 is a top plan view thereof;

FIG. 4 is a bottom plan view thereof;

FIG. 5 is a perspective view of another embodiment of FIG. 1 wherein a longitudinal bevel has been placed on the side opposite the faceted face seen in FIG. 1;

FIG. 6 is a side elevational view of FIG. 5;

FIG. 7 is a top plan view of FIG. 5;

FIG. 8 is a bottom plan view of FIG. 5;

FIG. 9 is a perspective view of another embodiment wherein an elongated bevel has been placed on the sides of the faceted face of FIG. 1;

FIG. 10 is a side elevational view of FIG. 9;

FIG. 11 is a rear elevational view of FIG. 9;

FIG. 12 is a top plan view of FIG. 9;

FIG. 13 is a bottom plan view of FIG. 9;

FIG. 14 is a perspective view of another embodiment wherein the faceted elongated bevel is wider and the remaining three sides have elongated bevels;

FIG. 15 is a side elevational view of FIG. 14 the opposite side being a mirror image thereof;

FIG. 16 is a rear elevational view of FIG. 14;

FIG. 17 is a top plan view of FIG. 14; and

FIG. 18 is a bottom plan view of FIG. 14.

I claim:

The ornamental design for a golf tee, as shown and described.
